UNITED STATES PATENT OFFICE.

ALBERT ALFRED CARPER, OF BALTIMORE, MARYLAND, ASSIGNOR TO THE CROWN CORK & SEAL CO., OF BALTIMORE, MARYLAND.

MEANS FOR BOTTLING GASEOUS LIQUIDS.

1,120,596.

specification of Letters Patent.

Patented Dec. 8, 1914.

Application filed December 1, 1908. Serial No. 465,533.

To all whom it may concern:

Be it known that I ALBERT ALFRED CARPER, a citizen of the United States, and a resident of the city of Baltimore, in the 5 State of Maryland, have invented a certain new and useful Means for Bottling Gaseous Liquids; and I do hereby declare that the following specification, taken in connection with the drawings furnished and forming a 10 part of the same, is a clear, true, and complete description of the several features of my invention.

One object of my present invention is to 15 so control the venting of gas from the bottle in relation to the supplying of the gaseous liquid that the pressure will rise in the filling chamber and bottle just before the bottle is closed, so that the bottle will be capped with a gaseous pressure 20 therein equal to that at the supply font.

Another object of my invention is to provide such means for venting air and gas from the bottle or other receptacle as will 25 secure a rapid fill.

Another object is to provide means for 30 venting from points at different heights in the bottle to get different filling levels.

Other objects of my invention will be 35 clear from the following description.

In the accompanying drawings, Figure 1 40 illustrates, in front elevation, one end of a machine, embodying several of the complete operative organizations shown; Fig. 2 is a sectional view of the head of the 45 machine; Fig. 3, Sheet 2, is a side elevation of the machine with the frame and shafting in section as parts of a "multiple" machine; Fig. 3^a is a top view of the bottle "carrier"; Fig. 4 is a sectional view of a 50 portion of the filling and capping head, differing from Fig. 2 in certain particulars of construction; Fig. 5, Sheet 3, is a plan or top view of the filling and capping head; Fig. 6, Sheet 4, illustrates, in side 55 view, a cam and its levers, and also an upper portion of the head; Fig. 7 illustrates, in section, the interior of the head, and in side view a hand rod for controlling gaseous pressure by hand; Fig. 8 is a similar section of the lower portion of the head, indicating a different mode of working; Fig. 9 is a section, on an enlarged scale, of a venting tube which is the central portion of the head; Fig. 10, Sheet 5, illustrates the 60 lower portion of the head with a bottle in

position and all ready for filling; Fig. 11 is a similar view showing the parts at the completion of the filling and capping operation; Fig. 12 is a top view of the bottom of the filling chamber, the top of a bottle in 65 position for filling, and a venting tube, in section, within the bottle.

My present invention relates to the type 70 of bottling machine disclosed in Letters Patent of the United States #1,012,984, granted to me December 26, 1911, and like 75 in said prior invention the present one, as to some of its features, may be carried into effect by a machine which embodies only the elements which form a single bottling mechanism, the invention, however, being capable of embodiment in a machine of multiple form in which a plurality of sets of such elements or bottling mechanisms are included.

The frame of the machines embodying the 80 invention may be of any suitable construction. In the particular machine selected to disclose the invention, the frame includes a main plate A; end plates, one of which is 85 shown at A'; a foot plate A²; two vertical posts, one being shown at A³, and a head plate A⁴.

A machine embodying the invention in 90 its best form will have its working parts 85 power driven, and while the means for transmitting power to the working elements may be varied within wide limits, in the particular machine illustrated the transmission is by a main shaft B carrying cams 90 for imparting some of the movements, and an upper counter shaft B² connected with the main shaft by a sprocket chain B', the said shaft B² carrying means for imparting other movements as will hereinafter appear.

Each set of bottling mechanism, whether 100 the invention be embodied in a machine of single or multiple form, will include a bottle presenting device, and while this device indicated generally at C, together with its 105 operating mechanism, may be varied widely in construction, I have shown it herein of substantially the same form as that illustrated in my prior patent above referred to, the said bottle presenting device being 110 slideable vertically in suitable bearings with which it has a splined connection to prevent turning, and being actuated from the main shaft by a cam C' and a yoke lever, the lat-

5 after bearing on a lock nut C^2 which is adjustable on the lower screw-threaded stem of the bottle presenting device. By this mechanism the bottle presenting device is
 10 given a reciprocating movement vertically to present the bottles to the filling mechanism and to the capping means hereinafter referred to. The immediate support for the bottle forming a part of the bottle presenting device may be of various forms, but in the particular machine shown I employ a yielding head or top C^3 upon which the bottle rests.

15 Machines embodying the invention will include suitable means for supplying liquid to the bottles to be filled, which means may be of widely different construction. In the form of the invention herein disclosed the liquid supplying devices delivers the liquid
 20 to be bottled through a filling chamber G , the bottle, prior to the delivery of the liquid, having been presented to the filling chamber by the bottle presenting device.

25 In bottling machines it is frequently desirable to bottle combinations of different kinds of liquid, such, for instance, as charged and still liquids, the latter being a flavoring extract known as "syrup". When, as in the machine shown, carbonated
 30 water having a flavoring extract added thereto is to be bottled, or when, for any reason, it is desired to fill a bottle with a combination of liquids, the liquid supplying devices and connections leading to the
 35 filling chamber will be of such a character as to provide for the proper delivery of the different kinds, and proportionate amounts of the different kinds of liquids. In the particular machine illustrated, a duct,
 40 F^2 is provided communicating with two sources of liquid supply. One of these is illustrated by the supply pipe marked "Water", which is connected with a suitable fountain or carbonating machine. The
 45 other source illustrated is the syrup pump F which is representative of any suitable form of device for supplying the syrup. The discharge of liquid, as carbonated water, through the duct F^2 may be controlled
 50 by a variety of means. In the particular construction shown this consists of a valve E pressed upwardly upon its seat by a suitable spring, said valve having an upwardly extending stem projecting above its housing. When syrup is to be used in bottling,
 55 the discharge thereof into the conduit F^2 may take place from the pump F in any suitable manner, as, for instance, by way of passages and check valves such as shown in
 60 the Patent #1012984, above mentioned.

65 In bottling liquids under pressure, the filling chamber should be tightly closed when the bottle has been placed in communication with the interior of the said chamber. The means for doing this may be

varied in form. In the construction illustrated this means includes a gasket G' carried by a ring G^2 movable vertically and suspended from the filling head by a pintle shown in Figs. 10 and 11. While the operating means for this gasket and ring may be varied within wide limits, in the construction illustrated, a yoke lever H is employed pivotally mounted on the housing of the filling head, the arms of said lever operating against the under side of lugs projecting from the ring G^2 , all as set forth in the above mentioned patent. The yoke lever H is operated by a rod H^2 from cams H' on the shaft B , as shown in Figs. 1 and 3. When the yoke lever is swung upwardly, the ring G^2 with the gasket G' is also moved upwardly, causing the gasket to be contracted for making tight packing contact with the bottle. When the gasket ring is dropped, the normal annular opening in the gasket is somewhat larger than the diameter of a capped bottle, to allow the bottle which has been filled and capped to be lowered and removed.

90 As in the patent above referred to, I prefer to control the supplying of the liquid or liquids to the filling chamber by the presence of the bottle in proper position for filling. Various means may be used for this purpose. One embodiment of a bottle-controlled liquid supply mechanism may consist, as in the particular construction illustrated, of a lever D pivotally mounted on the bottle presenting device C^3 , and spring pressed, as shown in Fig. 3^a, said lever, near its fulcrum, having gear teeth meshing with elongated teeth on a vertically reciprocating actuator rod D' , which is operated from a cam D^2 on the main shaft B , for instance, as in the patent above mentioned. The actuator rod D' in the particular construction illustrated is provided with a tappet E' for depressing and opening the water valve, and also a tappet arm F' arranged at a different angle from the tappet E' and above the same. The actuator rod, while in constant reciprocation, may be said to be normally inoperative in that so long as no bottle is present on the bottle presenting device C^3 for filling, the tappets on the actuator will not strike the water valve stem or engage the piston of the syrup pump, but when a bottle is placed on the bottle presenting device the lever D will be pressed back, the actuator rod will be rotated, and the tappets thereon brought into proper position to engage the stem of the water valve E and the piston of the syrup pump F , so that on the downward movement of the rod liquid from these two sources will be delivered to the duct F^2 to flow into the filling chamber, by the downwardly inclined port of Fig. 2.

110 In machines including the best embodiment

ments of my invention, means will be provided for applying closures to the filled bottles and these, preferably, will be adapted to apply metal sealing caps such, for instance, as caps of the well known "crown cork" type. While the closure applying means may be of a variety of forms and will, of course, vary according to the character of the closure employed, in the particular machine illustrated the closure applying mechanism includes a cap applying tool I located at the top of the filling chamber. This tool is tapered upwardly on its interior, and in the best construction it has associated therewith a capping plunger I' backed by a spring I², which bears on the flange I³, holding the same normally in gas-tight contact with the top of the filling chamber. The function of this capping plunger, when such is used, is to apply pressure to the top of the cap, thereby forcing the cork disk or other packing usually contained in the cap firmly against the bottle lip before or near the beginning of the cap applying operation, which consists in bending the flange of the cap inward so as to lock it to the bottle, this bending and locking resulting from forcing the bottle head with the cap thereon upwardly into the tapered throat of the tool I, the tapered walls of which, acting on the flange of the cap, bend it downwardly and inwardly, as is well known. The closures may be supplied to the bottles to be capped in various ways, but preferably they will be fed automatically into the filling chamber and positioned on the bottle heads. The cap supplying means, when such are employed, may vary widely in construction. In the particular construction illustrated, the caps will be held in a mass within a hopper L supported from the upper shaft B² and having a chute extending down therefrom, as in the patent above referred to. The hopper is provided with any suitable agitator for keeping the caps in free condition for feeding down the chute. The hopper, with the chute, can have oscillating movement about the shaft B²; and as a form of connection, representative of any which might be used, for moving the chute to and from the filling chamber, I show links L² and L³, the former being connected with the gasket controlling lever H to be operated simultaneously therewith. While the placing of the caps into the filling head may be accomplished in various ways, in the best construction the discharge of the caps into the filling head takes place through a cap port K in the side of the head, the lower end of the chute, for this purpose, being advanced, as shown in dotted lines in Fig. 10, to register with the cap port. Where, as in the particular machine illustrated, the bottles are to be filled with liquid under gaseous pressure and then capped by introducing the

caps through a cap port, means are provided for sealing the filling chamber gas tight at the cap port, and while such sealing means may assume various forms, in the particular machine illustrated a pad block K' is employed to seal the cap port K after the cap has been introduced, to be engaged with the bottles. The means for operating this pad block may vary within wide limits. In the particular construction shown it is mounted on the gasket controlling lever H, so that as this is raised to cause the contraction of the gasket to make a gas-tight contact with the bottle, the pad block will be forced to its seat around the cap port to seal the same gas tight. As the pad block is moved to seal the cap port, the cap chute is retracted to the position shown in Figs. 10 and 11. As, however, in the particular machine shown, the construction and operation of these parts is the same as in the patent above referred to, it is not necessary to describe them more at length herein. While the cap may be assembled with the bottle in various ways, in the particular construction shown I employ a cap finger K² for this purpose. The cap, when introduced into the cap port, is supported to one side of the axis of the filling chamber, as indicated in Fig. 10, its position being determined by abutments marked K² in the patent above referred to, against which the edge of the cap bears. The cap finger K² is spring pressed, as in the said patent, and when the pad block is in position to seal the cap port the said finger bears upon the edge of the cap, as shown in Fig. 10. After the bottle is filled it is thrust upwardly within the filling chamber from the position of Fig. 10 to that of Fig. 11. In its upward course its lip strikes the cap and tilts it up sufficiently to free it from the retaining abutments, whereupon it will be thrust into position over the head of the bottle by the spring-pressed cap finger, and it will then be carried up against the capping plunger I' and to the capping tool I. With a gravity cap feed, when such is used, as in the particular form of machine illustrated, means are provided for holding the caps in the chute when it is retracted from the cap port. While a variety of forms of devices for this purpose may be provided, in the particular machine shown a spring pin L' is employed, said pin being carried by an extension of the lever or link L³. When the chute is advanced into registration with the cap port, this pin is lifted to allow the lowermost cap, under the weight of the column of caps in the chute, to enter the cap port and assume the position shown in Fig. 10, against the abutments, and to one side of the center line of the filling chamber. When the cap chute is retracted, the spring pin L' engages the cap, which is

now lowermost, and holds the entire column of caps in the chute.

In the foregoing description I have indicated that in machines which are to include 5 any or all of the groups of mechanism, the construction thereof may assume a wide variety of forms, those chosen to illustrate these parts of my invention being representative of any suitable forms which may be 10 used. I will now refer to means of venting the gas and air from the bottle.

In bottling charged or carbonated liquids, the filling chamber, as above described, is provided with means for effecting a gas-tight closure thereof, leaving the interior of the bottle, however, in free communication with the said filling chamber. When this is done, it is usual to provide a venting conduit or passage to allow the escape of the air 15 which is driven out of the bottle by the entrance of the liquid thereinto. Machines embodying the invention in its best form will be provided with such venting conduit, and in the best constructions embodying the 20 invention this venting conduit will be open during the time the liquid is entering the receptacle and will be closed before the valve which controls the inflow conduit is closed. A construction in which the venting conduit 25 remains open as above stated and is closed before the inlet valve for the inflow conduit is closed possesses a marked advantage. The air in the receptacle to be filled is allowed to escape freely and rapidly during 30 the flow of the liquid into the receptacle, so that there is no back pressure on the entering current of liquid. When, however, the desired amount of liquid has entered the receptacle the shutting off or closing of the 35 venting conduit establishes a gas pressure in the filling chamber and receptacle which checks the inflow of the liquid, and the pressure in the receptacle will become equalized with the pressure in the carbonator or 40 source from which the liquid is obtained, so that at the time the inlet valve is closed and prior to the closure applying operation, a pressure of gas will have been established 45 in the receptacle which is equal to the gas pressure in the carbonator. In bottling carbonated liquids it is desirable to utilize the 50 full gas pressure of the carbonator and also to obtain the desired pressure of gas in the receptacle. In constructions in which the 55 inlet valve is closed before the venting or "snifing" as it is sometimes called is completed, there is almost invariably a loss of gas in the receptacle. In order, therefore, to obtain the desired pressure in the receptacle, it is necessary, in such machines, to 60 employ a higher pressure in the carbonator than it is desired ultimately to obtain in the receptacle, the extra amount of gas in the carbonator being wasted.

55 The particular means employed for effect-

ing the closing of the venting conduit prior to the closing of the inflow conduit may be varied within wide limits. In the particular construction illustrated, there is employed a venting tube M, Figs. 2, 4, 7, 8 and 9, having 60 ports M¹ and having at its lower end a small escape port leading into the interior of the tube. In a machine employing a capping plunger I preferably locate the vent tube within said plunger with its stem M' projecting above the shank I¹ of the same. Below the union of the stem and tube, in the particular construction chosen to illustrate this part of my invention, a collar M² is fixed on the tube against which a spring M³ is 65 bears, the upper end of the spring abutting against a head screwed into the shank I¹ of the capping plunger. This spring is under light tension and merely causes the tube to slide downwardly after it has been lifted, and enables the tube to yield should its lower end strike an obstruction. The extreme low position of the tube in relation to the bottle and filling chamber may be determined in various ways. As one means for 70 this purpose the collar M² may be employed which rests upon a seat in the capping plunger, as shown in Fig. 2, adjacent which a lateral port is provided in the capping plunger for the passage of air incident to 75 the vertical movements of the collar within the cylindrical space of the capping plunger. Means may be provided, variable within wide limits as to construction, for variably limiting the downward movement of the tube so that its lower end may occupy various heights in relation to the bottle to determine the line of fill. In the particular construction shown, and as representative of any means which may be used for the 80 purpose, I show a collar M⁴ on the stem of the tube above the tubular shank of the capping plunger, a thumb screw in the collar enabling it to be locked to the tube stem at different points thereon, recesses being indicated in the tube stem at various points in 85 Fig. 6. By this construction, or any other suitable construction devised for the purpose, provision is made for locating the lower end of the vent tube at different 90 heights in relation to the bottle as illustrated in Figs. 2, 7 and 8.

The vent tube itself may be variously constructed, but in the particular construction shown I employ a tube screw threaded internally at its lower end to receive a vent plug M⁵ having a small central bore for the escape of the gas and air in proper volume. Plugs having different sizes of bores may be furnished to secure variations in the venting 95 capacity for meeting different conditions as to liquids and pressures. A variety of ways may be provided whereby the venting may take place from different heights in the bottle, as above mentioned, and whereby the 100

venting may be cut off when the bottle has been filled to any one of the heights that may be desired. In the particular construction shown, I provide for the venting at 5 different heights by a series of ports M^1 , M^2 , M^3 located at different elevations, and extending through the capping plunger to connect with the space within the upper housing of the filling head, from which the 10 final discharge takes place through the pipe marked "Waste pipe". In the particular construction illustrated, when the vent tube is in its lowest position as shown in Fig. 2, the venting from within the bottle will take 15 place through the vent tube and the ports M^6 , M^7 . When the tube is in the position shown in Fig. 7, the filling line in the bottle will be higher than in the case just mentioned, and the venting will now take place 20 through the tube and the ports M^6 and M^8 , and if the tube is raised to the position shown in Fig. 8, the filling line will be still higher and the venting will now take place 25 through the port M^9 .

25 Machines embodying the invention in its best form will have the vent tube adjustable to occupy any one of a plurality of venting positions, and the venting will be controllable at all the venting positions of the tube. 30 While the means for doing this may vary in construction, I have described above one form of adjustment which is representative of any that might be used. So also the means for controlling the venting at all the 35 venting positions of the tube may be varied. In the particular construction shown, this control is exerted by simply raising the tube to bring the ports therein out of register with the escape ports above mentioned, the 40 tube being thus closed against the escape of gas or air.

The mechanism for operating the vent tube may vary within wide limits. I show one form of such mechanism herein as representative of any suitable form which may 45 be used. For this purpose a cam N on the shaft B^2 engages a roller on the short arm of a bell crank lever N' , the long arm of which is forked and engages the flange N^2 of a 50 sleeve which surrounds the stem of the vent tube, and is connected with said stem to move therewith as one body. The sleeve is slotted vertically, as shown in Fig. 6, to accommodate the clamp screw which secures 55 the stop collar M^4 on the stem of the vent tube. The long arm of the bell crank lever N' is jointed so that its outer end may be swung upwardly and rearwardly, as shown in dotted lines in Fig. 6, for putting the 60 cam and lever out of service, as when working the vent tube by hand, as will be hereinafter described. Below the long arm of the lever a chock or finger is pivotally mounted which can be swung upwardly to 65 support the lever N' out of service, and with

the vent tube lifted to its highest or inoperative position. The cam N is in two parts clamped to the shaft, and may be adjusted to accurate position on the shaft.

Referring to Fig. 4, it will be seen that 70 therein venting is indicated at only two points, both within a bottle, the cap plunger I' having but two sets of lateral ports M^1 , M^8 . In this form the cap plunger contains 75 an inner bushing through which the vent tube extends. The vent tube in this form is connected adjustably with its operating sleeve N^2 by a clamp nut engaging the screw-threaded upper end of the tube stem. The closing of the vent tube prior to the closing 80 of the inlet valve E may be effected in various ways, but in the particular construction shown it is due to the relative timing of the action of the cam N in lifting the vent tube to the action of the cam D^2 in controlling 85 the actuated rod D' .

As illustrating the fact that my vent tube may be operated by hand, I will describe, by way of an example of suitable means for the purpose, that which is shown in Fig. 7. 90 A flexible metal rod M^{10} is swiveled at the outer end of a lateral arm connected with the upper end of the vent tube stem. Upon this rod are suitable oval collars M^{11} , M^{12} , M^{13} , M^{14} , any one of which may rest upon 95 the lug or catch M^{15} on the housing of the filling head. Partial rotation of the hand rod will throw the collars out of line with the support M^{15} , or the flexibility of the rod will permit it to be swung aside for the 100 same purpose, so that the rod with the vent tube may be raised or lowered by hand. The collar lug M^{14} will enable the tube to be raised and held wholly within the plunger and out of service; the collar M^{13} will locate the end of the tube in the filling chamber, as shown in Fig. 8, and the collars M^{12} and M^{11} will locate the tube within a bottle, 105 respectively, at the highest and lowest points.

Briefly the operation of a machine embodying the invention is as follows: Referring now to Fig. 2, it will be understood that the bottle head and gasket are in gas-tight contact, and as if the interior of the 110 bottle were a part of the filling chamber; the snifting tube is at its lowest position within a bottle and with its vent closely approximating to the line or level to which the bottle is to be filled; the syrup and 115 charged water are progressively delivered laterally through the duct into the bottle; the air and gas displaced by the liquid, at first, is mainly forced into the filling chamber, and partly snifted through the vent tube, and as the pressure in the chamber 120 increases, the venting by the tube is proportionately increased, and to a degree which will prevent a pressure in the chamber, which would obstruct the inflow of the 125

liquid, thus assuring a rapid fill. The liquid in the bottle, on reaching the lower end of the vent tube, cuts off the further escape of gas, and the pressure in the chamber is promptly raised to a degree which balances the pressure under which the charged water is delivered, and so holds it back in its duct; the water valve being still open, the vent tube is promptly lifted, and made 5 inoperative, the bottle head and neck is at the same time forced into the chamber until the bottle releases the cap at the cap port and carries it up into compressing contact with the cap plunger, thus initially, by the 10 packing in the cap, tightly closing the bottle just before, or about at, the time the water valve closes and absolutely cuts off the liquid. The bottle is thus initially closed at a time when its contents are under a 15 gaseous pressure equal to or greater than that at which the charged water is delivered to the chamber. The continued upward movement of the bottle causes the capping tool to lock the cap to the bottle, as 20 shown in Fig. 11, and the lifting of the cap plunger by the bottle enables the gas to escape from the chamber into the waste pipe which, at all times, receives the air, gas and any little liquid vented through the tube. 25 The retirement of the vent tube is closely followed by the entering bottle head and neck, which, in bulk, occupies much more space in the chamber than the tube did, thus tending to increase the pressure in the chamber and bottle up to the moment the cap plunger is lifted after first having tightly closed the bottle by compressing the cap 30 packing.

It will be observed that my invention 40 permits initial venting, *i. e.*, while the bottle is in course of filling, up through the capping tool and capping plunger, and axially in relation to the filling chamber and bottle, and furthermore, it will be observed 45 that the vent tube, in one aspect, forms a valve located above the capping tool and within the housing, said valve being seated in the capping plunger and controlling an outlet passage or passages leading there- 50 from into the housing and thence to the outside. This provides a compact and simple construction in which the functions of the well known parts, such as the capping tool, the capping plunger, its housing, and the 55 filling chamber, are not interfered with, and provides for initial venting directly upward from the bottle and filling chamber.

While the machine which has been chosen 60 to illustrate my invention is efficient in carrying it into effect, it will be understood that the mechanisms employed may be varied within wide limits without departing from the scope of the invention as claimed.

It will also be understood that features of 65 my invention may be used separate from

the other features shown and described, and such independent use is within the scope of my invention as claimed.

Having thus described and ascertained the nature of my said invention and in what manner the same is to be performed, I declare that what I claim is:

1. In a bottle filling machine, the combination with a filling chamber, of means for delivering gaseous liquid thereto, means for maintaining a bottle in gas-tight communication therewith, automatic means for enabling the gas to escape continuously until the filling operation has been nearly completed, positively operated means timed for cutting off automatically the escape of gas after a prescribed filling period has elapsed to allow the pressure within the filling chamber and bottle to rise, and means for capping the bottle while its contents are under said gaseous pressure, substantially as described. 75

2. In a bottle filling machine, the combination with a filling chamber, of means for delivering gaseous liquid thereto, means for maintaining a bottle in gas-tight communication therewith, a vent tube for enabling the gas to escape continuously therethrough from the filling chamber and bottle until a filling operation has been nearly completed, means for then automatically withdrawing the vent tube and cutting off the escape of gas to allow the pressure within the filling chamber to rise, and means for capping the bottle while its contents are under said 90 gaseous pressure and while the vent tube is withdrawn, substantially as described. 95

3. In a machine for bottling gas-charged liquids, the combination of a filling chamber, means for supplying the gaseous liquid under pressure to the filling chamber and bottle and cutting off the same, means for forming a gas tight seal between said filling chamber and the mouth of the bottle, a vent tube, means for automatically moving the vent tube into and from the bottle, and capping means for capping the bottle while its mouth is held in connection with the filling chamber, said vent tube being continuously open for venting during the inflow of the 105 gas-charged liquid and being closed to shut off the venting before the supply of gaseous liquid is cut off, substantially as described. 110

4. In a bottle filling and capping machine, the combination with a filling chamber having means for forming a gas tight seal with the bottle mouth, capping means, a tubular spring-actuated cap plunger, provided with a lateral port, of a slidably vent tube within the cap plunger having a venting aperture and with a lateral port, said tube being closed against venting when raised, means for projecting said vent tube below the head of the plunger, for venting service, and for lifting it and terminating 120 125 130

the venting prior to the lifting of the cap plunger in the capping operation and means for supplying gaseous liquid to the filling chamber and bottle, substantially as described.

5. In a bottle filling and capping machine, the combination of a filling chamber having means forming a gas tight seal with the bottle mouth, capping means, a tubular capping plunger having a lateral port, a vent tube closed at its top, slidable within the plunger, and provided with a venting aperture and with a lateral opening, the latter registering with the plunger port for venting only when the tube is lowered for venting service and means for supplying gaseous liquid to the filling chamber and bottle, substantially as described.

6. In a filling and closure applying machine for liquids under pressure, the combination with a filling chamber, and means for applying a closure to the bottle mouth while in said chamber, of means for forming a gas tight seal between said chamber and the mouth of the receptacle, an inflow conduit for the liquid, a venting conduit open during the liquid inflow, positively operating means for automatically closing the venting conduit, said means being timed to act after a prescribed filling period has elapsed, and positively operating means for automatically closing the inflow conduit after the venting conduit has been closed, and closure applying means.

35 7. In a filling and closure applying machine for liquids under pressure, the combination with a filling chamber, and means for applying a closure to the bottle mouth while in said chamber, of means for forming a gas tight seal between said chamber and the mouth of the receptacle, an inflow conduit, a vent tube open during the inflow of the liquid and movable through the filling chamber, means for closing the vent tube when the desired amount of liquid has entered the receptacle, means for closing the inflow conduit after the vent tube has been closed, and closure applying means.

8. In a filling and closure applying machine for liquids under pressure, the combination with a filling chamber, of means for forming a gas tight seal between said chamber and the mouth of the receptacle, and means for applying a closure to the said mouth of said receptacle while in said chamber, an inflow conduit, a vent tube movable through the filling chamber into the mouth of the receptacle, said tube having ports, a discharge conduit with which the ports are register when the vent tube is in operative position, means for moving the vent tube to bring its ports out of register with the discharge conduit when the desired amount of liquid has entered the receptacle, means for closing the inflow conduit after

the vent tube has been moved, and closure applying means.

9. In a filling and closure applying machine for liquids under pressure, the combination with a head provided with a filling chamber and closure applying means, of means for forming a gas tight seal between the chamber and the mouth of the receptacle, an inflow conduit for the liquid, a venting conduit open during the liquid inflow, positively operated means for automatically closing the venting conduit, said means being timed to act after a prescribed filling period has elapsed, means for automatically closing the inflow conduit after the venting conduit has been closed, a support for the receptacle, and means for producing a relative movement between the support and the closure applying means to effect the application of the closure.

10. In a filling and closure applying machine for liquids under pressure, the combination with a head provided with a filling chamber and closure applying means, of means for supporting closures in the head, means for forming a gas tight seal between the chamber and the mouth of the receptacle, an inflow conduit for the liquid, a venting conduit open during the liquid inflow, positively operated means for automatically closing the venting conduit, said means being timed to act after a prescribed filling period has elapsed, means for automatically closing the inflow conduit after the venting conduit has been closed, a support for the receptacle, and means for producing a relative movement between the support and the closure applying means to effect the application of the closure.

11. In a filling and closure applying machine for liquids under pressure, the combination with a head provided with closure applying means and a filling chamber, of means for supporting a receptacle beneath the chamber, means for forming a gas tight seal between the chamber and the mouth of the receptacle, an inflow conduit for the liquid, a vent tube open during the inflow of the liquid, means for moving the vent tube through the head into the filling chamber and for closing the vent tube, said means being timed to act for closing the vent tube, after a prescribed filling period has elapsed, means for closing the inflow conduit after the venting tube has been closed, and means for producing a relative movement between the head and the receptacle support to effect the application of the closure.

12. In a filling and closure applying machine for liquids under pressure, the combination with a head having a filling chamber, means for supplying gaseous liquid to the bottle, a bending die mounted in the head and located above the filling chamber, a closure positioning means operating in the

- head, a sleeve having a discharge port and mounted in the head, a vent tube movable through the sleeve, said tube being provided with a discharge port for the venting therethrough and thence through the port in the sleeve, an inflow conduit for the liquid, means for opening and closing said conduit, means for lifting the vent tube, said means being timed to act after a prescribed filling period has elapsed and before the closing of the inflow conduit, said vent tube being closed against venting when lifted, a support for the receptacle, and means for effecting a relative movement between the support and the head to effect the application of the closure, substantially as described.
13. In combination, a filling chamber, a capping tool therein, means for sealing the chamber, bottle presenting means, means for delivering liquid to the filling chamber and thence into the bottle, and a vent tube to extend into the bottle through the capping tool, substantially as described.
14. In combination with a filling chamber, a capping tool therein, means for sealing the chamber, means for delivering liquid thereto and thence to the bottle, and a vent tube movable in relation to the filling chamber and bottle and to and from a point below the capping tool and continuously open when in position for venting, substantially as described.
15. In combination, a filling chamber, bottle presenting means, means including a filling valve for delivering gas charged liquid to the filling chamber and thence into the bottle, a vent tube to be opened and closed and movably supported to enter and withdraw from the bottle, and means for closing the filling valve after the vent tube is closed, substantially as described.
16. In combination, a filling chamber, means for making a gas tight seal between the bottle mouth and the filling chamber, a capping tool in the filling chamber, bottle presenting means, liquid delivery means to supply liquid to the filling chamber and thence to the bottle, a vent tube movable to and from a position within the bottle, said vent tube being closed by its movement from the bottle for the capping operation, substantially as described.
17. In combination in a bottling machine, a filling chamber, means for making a gas tight seal between the bottle mouth and the filling chamber, a capping tool and a capping plunger in the filling chamber, bottle presenting means, means for delivering liquid to the filling chamber and thence to the bottle, and a vent tube movably mounted in the capping plunger, substantially as described.
18. In combination in a bottling machine, a filling chamber, means for making a gas tight seal between the bottle mouth and the

- filling chamber, a capping tool fixed in the filling chamber, a movable capping plunger projecting into the capping tool, a vent tube slideable in the capping plunger and into and from the bottle, means for delivering liquid to the filling chamber and thence to the bottle, and bottle presenting means, substantially as described.
19. In combination in a bottling machine, a filling chamber, means for making a gas tight seal between the bottle mouth and the filling chamber, a capping tool in the filling chamber, bottle presenting means, means for delivering liquid to the filling chamber and thence to the bottle, a vent tube movable to and from position within the bottle, means for supporting the bottle caps to one side of the axial line of the filling head, and a cap projecting device for moving the cap over the bottle after the vent tube withdraws and as the bottle rises.
20. In combination in a bottling machine, a filling head, means for making a gas tight seal between the bottle mouth and said head, bottle presenting means, means for supporting bottle caps to one side of the axial line of the filling head and of the bottle when in place to be filled, a vent tube movable to and from position within the bottle, and a cap projecting device for moving the cap over the bottle after the tube is withdrawn and as the bottle rises.
21. In a bottle filling and capping machine, the combination of a filling chamber, means for making a gas tight seal between the bottle mouth and the filling chamber, closure applying means in said filling chamber, liquid supply means, a vent tube, mechanism to move the vent tube into and out of the bottle to any one of a plurality of venting positions, and means for cutting off the venting at all the venting positions of the tube before the liquid supply is cut off, substantially as described.
22. In a bottle filling machine, the combination of a filling chamber, means for forming a gas tight seal between the same and the mouth of the bottle, means for supplying gas charged liquid to the bottle, a vent tube, mechanism to move the vent tube into and out of the bottle to any one of a plurality of venting positions, and means for stopping the venting by the lifting of the tube from either of its venting positions, substantially as described.
23. In a filling and capping machine, the combination of a filling chamber, means for making a gas tight seal between the bottle mouth and the filling chamber, a capping tool in the filling chamber, means for continuously supplying gaseous liquid to the filling chamber and thence into the bottle until the cap is seated on the bottle, a vent tube for continuously venting from the interior of the bottle until the liquid reaches

the filling tube, and means for lifting the vent tube and closing the same, substantially as described.

24. In a filling and capping machine, the combination of a filling chamber, a capping tool therein, means for forming a gas-tight seal between the chamber and the mouth of the receptacle, an inflow conduit for the liquid, a venting conduit, means for automatically closing the venting conduit before the inflow conduit is closed, a support for the bottle, and means for producing a relative movement between the bottle support and the filling chamber after the venting 10 ceases, causing the bottle head to enter the filling chamber and coöperate with the capping tool to seat and lock the cap thereon, substantially as described.

25. In combination in a bottle filling and closure applying machine for liquids under pressure, a filling chamber having means to make gas-tight contact with the bottle, means for supplying gaseous liquid under pressure, a capping tool in the filling chamber, a vent tube, means for moving the same through the filling chamber and to and from venting position, said vent tube being closed when raised, a bottle support and means for

producing a relative movement between said support and capping tool after the vent tube 30 is raised, substantially as described.

26. In combination in a filling and capping machine, a filling head, means for making a gas tight seal between the bottle mouth and the filling head, a capping tool in the filling head, a capping plunger extending down within the capping tool, a vent tube 35 extending through the capping plunger, means for moving the vent tube down into venting position and withdrawing it therefrom, said vent tube being closed when raised, an inflow conduit with means controlling the same, means for moving a cap into position between the bottle head and the capping plunger when the vent tube 40 withdraws from the bottle, a bottle support, and means for producing a relative movement between the same and the capping tool when the vent tube is raised, substantially as described. 45

In testimony whereof, I affix my signature in presence of two witnesses.

ALBERT ALFRED CARPER.
